UNITED STATES PATENT OFFICE.

CLARENCE T. EVANS AND WILLIAM H. HOLDER, OF MILWAUKEE, WISCONSIN, ASSIGNEES TO THE CUTLER-HAMMER MFG. CO., OF MILWAUKEE, WISCONSIN, A CORPORATION OF WISCONSIN.

ELECTRIC SWITCH.

Application filed September 27, 1919. Serial No. 326,896.

This invention relates to electric switches and is particularly applicable to electromagnetically operated switches of large current carrying capacity.

5 In many instances where switches of large current carrying capacity are required and especially in submarine installations the limited space available precludes the use of electromagnetic switches as heretofore designed because of their lateral dimensions and the present invention has among its 10 objects to provide an electromagnetic switch particularly adapted for such installations.

Another object is to minimize the inherent 15 sluggishness of operation of such switches.

Another object is to provide an electromagnetic switch for the aforesaid and other purposes having its parts readily accessible from the front thereof for inspection and 20 also for removal and replacement when necessary.

Various other objects and advantages will hereinafter appear.

The accompanying drawings illustrate 25 one embodiment of the invention which will now be described, it being understood that the embodiment illustrated is susceptible of various modifications falling within the scope of the appended claims.

30 In the drawings—

Figure 1 is a side elevational view of an electromagnetically operated switch which embodies the invention;

Figs. 2, 3 and 4 are detail views, partly 35 in section, of certain parts thereof; and,

Fig. 5 is a front elevational view of a plurality of switches embodying the invention.

The switch shown in the drawings is 40 mounted upon a horizontally arranged insulating panel 1 and includes a movable switch arm 2 having mounted thereon a contact plate 3 and two auxiliary contact levers 4, a stationary contact 5 to co-operate with 45 contact plate 3 and two auxiliary carbon arcing contacts 6 to co-operate with auxiliary contact levers 4. The arm 2 is operable electromagnetically by a pair of solenoids 7 through the medium of a triple arm lever 8 and a link 9. The switch is adapted to complete the circuit from a terminal post 10 at the rear of panel 1 through a coil 11 of a blowout device to a terminal post 12 at the front of panel 1.

The switch arm 2 and contact levers 4 are 55 rotatably mounted on a shaft 13 supported by upright lugs 14 on a bracket 15, said shaft 13 fitting in notches 16 in the rear of said lugs and being secured in place by cap screws 17 passing through said lugs from 60 the front thereof. The switch arm 2, as best shown in Figs. 3 and 4, comprises a casting having spaced upright arms 18 connected at their upper ends by a cross piece 19 and at their lower ends by a forwardly 65 projecting arm 20 pivotally connected at 21 to the lower end of link 9. Contact plate 3 is mounted on the rear of arms 18 and is electrically connected to terminal post 12 by a flexible lead 22 while contact levers 4 are 70 arranged side by side between said arms and are also electrically connected to terminal post 12 by flexible leads 23. The auxiliary contact levers 4 extend upwardly in front of cross piece 19 and each is provided with an 75 arcing tip 24 and is yieldingly held against the upper end of contact plate 3 by a conventional tensioning device 25 arranged intermediate its ends.

The stationary contacts 5 and 6 are mounted upon an upright extension 26 of a bracket 27, the arcing contacts 6 being secured to the upper end of said extension in the usual manner and the contact 5 being arranged below said arcing contacts and secured to 80 said extension by cap screws 28. As best shown in Fig. 2 the contact 5 instead of consisting of a single group of laminæ, as has heretofore been the practice, is divided into groups of laminæ 5^a and 5^b and terminal 85 leads 29 and 30 are provided for connecting said groups to extension 26. The leads 29 and 30 are clamped to extension 26 by cap screws 31 and the lead 29 is clamped intermediate the groups 5^a and 5^b while the lead 90 30 is clamped on the outer face of the latter group. This arrangement tends to augment the current carrying capacity of the contact since the same insures a substantially uniform distribution of the current throughout the various laminæ thereof.

The brackets 15 and 27 are secured to panel 1 by cap screws 32, the latter being supported on the former but insulated therefrom by insulating plates 33 and the bracket 105 15 being insulated from said cap screws by insulating bushings 34. The bracket 27 is electrically connected to one terminal of the

blowout coil 11, the other terminal of said coil being electrically connected to terminal post 10. The coil 11 is self supporting and to facilitate manufacture thereof the same is made in two parts consisting of an inner coil 11^a and an outer coil 11^b surrounding the former. Coil 11 carries an insulated core 35 and pole pieces 36 arranged on opposite sides of the arcing contacts 6 and 24 and secured to said core by a bolt 37. The pole pieces 36 are insulated from coil 11 by insulating washers 38 and are provided on their outer ends with an insulating chute or barrier consisting of side plates 40, a rear plate 41 and a top plate 42, all of said plates being preferably formed of asbestos board. The rear plate 41 is secured between pole pieces 36 by bolts 43 and is arranged to engage a shoulder 44 on bracket 27 to support said pole pieces. The side plates 40 are secured together by bolts 45, the pole pieces 36 being cut away as shown in Fig. 1 to clear said bolts and insulating bushings 46 serve to maintain said plates in proper spaced relation and to protect the bolts 45 from arcs. The side plates 40 are supported on their lower edges by inwardly extending lugs 47 (Figs. 1 and 2) on the lower edges of pole pieces 36 and each is provided on its upper edge with a shoulder 48. Top plate 42 is removably secured to the upper edges of pole pieces 36 by cap screws 49 and engages shoulders 48 on side plates 40 to maintain the latter in position.

35 The solenoids 7 are mounted above the switch within a substantially rectangular magnetic frame consisting of a part 50 having feet on the rear thereof for securing the same to a suitable support such as a channel member 51 and a front member 52 removably secured to part 50 by cap screws 53. The solenoids 7 are arranged horizontally and one above the other and each is provided with a non-magnetic sleeve 54, a stationary core 55 and a plunger 56. The stationary core 55 of the upper solenoid is secured to the rear wall of part 50 by screws 57 and the sleeve 54 thereof fits within a bore in front member 52 while the stationary core 55 of the lower solenoid is secured to front member 52 by screws 58 and the sleeve 54 thereof fits within a bore in the rear wall of part 50. The triple arm lever 8 is rotatably mounted on a shaft 60 arranged intermediate the solenoids 7 and carried between lugs 61 on front member 52. The lever 8 has an upwardly extending arm 8^a pivotally connected by a pin 62 to the plunger 56 of the upper solenoid, a downwardly extending arm 8^b pivotally connected by a pin 63 to the plunger 56 of the lower solenoid and a forwardly projecting arm 8^c having its extremity pivotally connected to the upper end of link 9. Thus upon simultaneous energization of the sole-

noids the plunger 56 of the upper solenoid is attracted to the left and the plunger 56 of the lower solenoid to the right whereby said plungers act together to rotate the lever 8 in a counter-clockwise direction for closure 70 of the switch. For a purpose hereinafter set forth solenoids 7 are wound to provide for independence of the magnetic circuits thereof, such circuits being obtained by causing the flux to traverse the respective plungers 75 of said solenoids in the same direction.

With the aforescribed arrangement of parts it is possible to provide an operating device of exceedingly small lateral dimensions. The lateral space required by the 80 operating device is substantially the same as that required by the switch and as shown in Fig. 5 it is thus possible to mount several switches side by side in a very close relation. Also, it has been found that the employment of a plurality of operating windings with independent magnetic circuits instead of a single larger winding provides for 85 quicker operations of the switch. The time lag of such a switch is largely due to self induction of its operating means and the use of a plurality of windings having independent magnetic circuits minimizes the self inductance of the means, the independent magnetic circuits providing for a negligible mutual inductance of such windings. 95

Where several switches are mounted side by side as shown in Fig. 5, the various parts of any of the same can be removed or replaced from the front thereof without disturbing the adjacent switch or switches. Removal of cap screws 17 disconnects shaft 13 from lugs 14 and upon removal of link 9 and disconnection of flexible leads 22 and 23 from terminal 12 the switch arm 2 and auxiliary contact arms 4 can be readily removed as a unit. Removal of these parts renders the laminated contact 5 and arcing contacts 6 readily accessible from the front of the switch. Also, if necessary, the various parts of the insulating chute can be readily removed from the front of the switch. Removal of screws 49 disconnects top plate 42 from the pole pieces 36 and upon removal of said plate both of the side plates 105 can be removed by sliding the same upwardly until the bolts 45 clear the upper edges of the pole pieces and then moving the same forwardly out of engagement with said pole pieces. Front member 52 together with the parts carried thereby is also removable from the front of the switch upon removal of screws 53, disconnection of pin 63 from lever 8 and removal of the holding screws 58 for the stationary core 55 of the lower 110 solenoid. Removal of member 52 renders the operating windings 7 accessible for inspection and repair. 115

To insure easy operation of the plungers 56 within their respective sleeves 54 the same 120

are held out of engagement therewith by rollers 64 and 65 rotatably mounted on the rear of part 50. The roller 64 supports the rear end of plunger 56 of the upper solenoid 5 by engagement with pin 66 secured to said plunger and extending through an opening in the stationary core 55 while the roller 65 supports the rear end of plunger 56 of the lower solenoid by direct engagement there-
 10 with. For providing relative adjustment of the plungers 56 the pins 62 and 63 are threaded into their plungers 56 whereby upon disconnection of the same from lever 8 either can be adjusted to vary the position 15 of its respective plunger relative to the other plunger. Link 9 is made adjustable to vary the position of switch arm 2 relative to the lever 8 and is also constructed to provide proper insulation between the switch and the 20 operating device. Link 9 comprises a length of pipe 67 connected at its upper end by an insulating coupling 68 to an eye member 69 and at its lower end by a sleeve 70 and an insulating coupling 71 to an eye member 72.
 25 The sleeve 70 has a threaded connection with pipe member 67 whereby upon disconnection of eye member 72 from switch arm 2 the same can be adjusted to vary the length of link 9.
 30 In certain installations it is desirable to provide for manual operation of the switch and for this purpose a lever 75 is rotatably mounted on shaft 60 of the operating device and a cam 76 is mounted in front of said device to actuate said lever. The lever 75 is provided with an adjustable pin 77 to engage the end of pin 62 and is also provided with a roller 78 to ride upon the face of the cam. The cam 76 is so shaped that upon 35 rotation thereof the same moves the lever 75 in a counter-clockwise direction for closure of the switch. The cam 76 can be mounted in front of the operating device in any suitable manner and where it is desired to operate several switches in a definite sequence the several cams for the switches can be secured to a shaft 79, as shown in Fig. 5, and an operating handle 80 can be provided for rotating said shaft.
 40

50 What we claim as new and desire to secure by Letters Patent is:

1. In an electric switch, the combination with a movable switch element, of electro-
 55 magnetic means to actuate said element, said means including a pair of solenoids having their windings arranged side by side and vertically adjacent each other, said wind-
 60 ings having independent magnetic circuits through separate metallic paths to minimize the mutual inductance thereof and thereby minimize the time lag in operation of said element.

2. In an electric switch, the combination with a movable switch element of a plurality 65 of electromagnets arranged side by side and

adjacent each other with their axes in a vertical plane corresponding substantially to the plane of movement of said element, said electromagnets having independent magnetic circuits, members to be attracted by said electro-magnets and means connecting said members to said switch element for operation of said element by said electromagnets jointly.

3. In an electric switch, the combination 75 with an upright switch arm, of a pair of solenoids arranged one above the other and at one end of said arm with their axes in a vertical plane corresponding substantially to the plane of movement of said arm, said so solenoids having independent magnetic circuits, and linkage connecting the plungers of said solenoids to said arm for operation of said arm by said solenoids jointly.

4. In an electric switch, the combination 85 with an upright switch arm, of a pair of operating means therefor including horizontally disposed solenoids arranged above said switch arm with their axes in a plane corre- 90 sponding substantially to the plane of move-
 ment of said arm, said solenoids being adapted upon simultaneous energization to move their plungers in opposite directions, a lever pivotally connected to said plungers and having a fixed pivot intermediate the 95 same and a link operatively connecting said lever and said switch arm.

5. The combination with a switch, of an operating device therefor including a mag- 100 netic frame, a pair of solenoids mounted side by side within said frame, said solenoids having independent magnetic circuits and being adapted upon simultaneous energiza- 105 tion to attract their plungers in opposite directions and an operating lever for said switch pivotally mounted on said frame at a point intermediate said solenoids, and hav- 110 ing oppositely extending arms pivotally connected to the plungers of said solenoids.

6. The combination with a switch, of an 110 operating device therefor including a sub-
 stantially rectangular magnetic frame hav-
 ing open sides and a removable front mem-
 ber, a pair of horizontally arranged solenoids mounted one above the other within said 115 frame and adapted upon simultaneous ener-
 gization to attract their plungers in opposite
 directions and an operating lever for said
 switch pivotally mounted on the front of said
 frame at a point intermediate said solenoids, 120 and having oppositely extending arms pivot-
 ally connected to said plungers.

7. The combination with a switch, of an 125 operating device therefor including a sub-
 stantially rectangular magnetic frame hav-
 ing open sides and a removable front mem-
 ber, a pair of horizontally arranged solenoids mounted one above the other within said 130 frame and adapted upon simultaneous ener-
 gization to attract their plungers in opposite

directions, rollers rotatably mounted on the rear of said frame for supporting the rear ends of said plungers and an operating lever for said switch pivotally mounted on the front of said frame and having arms pivotally connected to the front ends of said plungers.

8. The combination with a switch, of an operating device therefor including a pair of solenoids mounted side by side and adapted upon simultaneous energization to attract their plungers in opposite directions, a rotatable operating lever for said switch con-

nected to said plungers for operating in one direction by said solenoids jointly, a manually operated cam and an operating connection between said cam and said lever for effecting movement of said lever in the aforesaid direction upon actuation of said cam, said connection being adjustable to vary the throw of said lever effective by said cam.

In witness whereof, we have each hereunto subscribed our names.

CLARENCE T. EVANS.
WILLIAM H. HOLDER.
